CLAIM

The ornamental design for a security enclosure for display and storage of articles, as shown and described.

DESCRIPTION

FIG. 1 is a front elevational view of a security enclosure for display and storage of articles showing our new design;
FIG. 2 is a right side elevational view thereof;
FIG. 3 is a top plan view thereof;
FIG. 4 is a left side elevational view thereof;
FIG. 5 is a rear elevational view thereof;
FIG. 6 is a bottom plan view thereof; and,
FIG. 7 is a top perspective view thereof with a portion broken away to show the mirrored inside surface of the rear wall.
